PISTON SKIRT EXPANDER

Filed June 9, 1932

Inventor
Ralph R. Teetor

By Rector, Hubben, Davis and Macaulay, Oct 1955.

UNITED STATES PATENT OFFICE

RALPH R. TEETOR, OF HAGERSTOWN, INDIANA, ASSIGNOR TO THE PERFECT CIRCLE COMPANY, OF HAGERSTOWN, INDIANA, A CORPORATION OF INDIANA

PISTON SKIRT EXPANDER

Application filed June 9, 1932. Serial No. 616,903.

My invention relates to pistons adapted for use in internal combustion engines and the like and more particularly to means for expanding a split piston skirt in order to eliminate piston "slapping", excessive oil consumption and blow-by and other defects.

It is a well-recognized fact that some pistons, and particularly those having split skirts formed of metal, such as aluminum, wear rather rapidly with attendant "piston-slap", excessive oil leakage past the piston ring and greatly diminished power. The principal object of my invention is to provide a novel piston skirt expander which eliminates these faults. To this end I have provided an expander which is simple in structure, efficacious in use, and readily adapted for use with various types of pistons without the necessity of performing any special operations on the pistons.

With the above and incidental objects in view, the invention consists in certain novel features of construction and combination of parts, the essential elements whereof are recited in the appended claims, and the preferred form of embodiment of which is described in detail hereinafter and illustrated in full in the accompanying drawing, which form part of this specification.

30 Of said drawing

Fig. 1 is a bottom plan view of a piston having my improved expander applied thereto;

Fig. 2 is a side view of the expander alone; and

Fig. 3 is a side view of the piston partially broken away to show part of the expander in position within the piston.

Referring to Figs. 1 and 3, I have shown, for illustrative purposes only, a piston having a head 5 and a skirt 6 which is provided with a vertical slot 7 in one side. Parallel webs 8 depend from the head and these webs carry piston pin bosses 9 carrying a piston pin 14. Except where the webs are joined to the head, the head is separated from the upper edge of the skirt by circumferential slots 10. The vertical slot 7 extends from the approximate center of one of these slots 10 to the lower edge of the skirt.

My expanding device 12 is preferably formed from a strip of spring steel and it is bent into its rectangular shape with the free ends 13 curved and contacting at 17. After the expander is placed in the piston, 55 the piston pin 14 is inserted into the openings 15 in the sides of the expander. The rear end of the expander contacts at the bends 16 with the interior wall of the piston opposite the slot 7. The free curved ends 13 contact with the interior wall of the piston at either side of the slot 7. With the expander in this position the bends 16 of the expander and the free ends 13 of the expander press firmly in opposite directions 65 against the skirt and at the same time the sides of the expander, which become bowed, press firmly against the facing edges of the piston pin bosses with the result that the expander expands the skirt and maintains it in 70 expanded condition so that it snugly fits the cylinder walls, thus avoiding piston slap and excessive blow-by and oil consumption. The slots 15 are slightly elongated to accommodate any movement of the expander 75 during its operation.

I preferably slot, as at 18, the free curved ends 13 of the expander to give these ends additional resiliency and to assure that they press more uniformly against the piston wall. 80 I also preferably, though not necessarily, strike out sharp lips 19 at the upper and lower edges of these curved ends 13 and also at the upper and lower edges of the bends 16 so that these lips may bite into the metal 85 of the piston skirt and better anchor the expander in position.

It is now evident that my invention is admirably adapted to perform the functions first stated. The expander is extremely simple, highly efficient, susceptible of use with various types of pistons now on the market, and readily applied to a piston without the necessity of performing special operations on the piston or using special tools.

I claim:

1. In combination with a piston having a skirt with a vertical slot, of a diametrically extending expander formed of spring metal and having free ends contacting each other 100

- and engaging the interior of the piston on either side of the slot and adjacent thereto.
2. In combination with a piston having a slotted skirt, piston pin bosses and a piston pin, of a spring expander extending across the piston substantially at right angles to the piston pin and contacting with and exerting pressure against the facing ends of said bosses and also against the piston skirt intermediate the bosses.
3. In combination with a piston having a skirt with a slot and a piston pin, of a skirt expander carried by the piston pin and engaging the skirt on each side of said slot.
4. In combination with a piston having a skirt, a piston pin and piston pin bosses, of a skirt expander formed of spring metal and disposed between the facing edges of the bosses and extending across the skirt, the expander having holes through which said piston pin extends.
5. In combination with a piston having a skirt with a slot, piston pin bosses and a piston pin carried by said bosses, of a skirt expander through which the piston pin projects and which engages the facing edges of the bosses and against the skirt on each side of said slot.
6. In combination with a piston having a skirt with a slot, piston pin bosses and a piston pin carried by said bosses, of a skirt expander having apertures through which the piston pin projects and which presses against the bosses and against the skirt on each side of said slot and also against the skirt opposite said slot.
7. In combination with a piston having a slotted skirt, of an expander having spring inwardly curved ends contacting with each other and engaging the piston skirt to expand the piston.
8. In combination with a piston having a skirt with a slot, of an expander formed of a single piece of flat spring metal, the expander being generally polygonal in shape and having curved ends in contact with the piston skirt on either side of said slot and adjacent thereto.
9. In combination with a piston with a skirt having a slot, piston pin bosses and a piston pin, of an expander formed of a single piece of flat spring metal, the expander being generally polygonal in shape and having curved ends in contact with each other and engaging the piston skirt on either side of and adjacent to said slot, the sides of the expander having holes through which the piston pin extends and said sides pressing against the ends of said bosses.
10. The combination of a piston having a slotted skirt, of an expander formed of spring metal having curved ends contacting with each other and engaging the piston skirt to expand the piston, and sharp points on said expander biting into the metal of said piston.
11. In combination with a piston having a slotted skirt and a piston pin, of a spring expander extending across the interior of the piston substantially at right angles to the piston pin for expanding the skirt the expander being carried by the piston pin, and sharp points on the expander biting into the metal of the skirt.
12. A piston skirt expander formed of spring metal and being generally polygonal in shape and having normally contacting reversely curved ends.
13. A piston skirt expander formed of flat spring metal and having reversely curved ends, the same ends being slotted transversely.
14. A spring expander generally polygonal in shape and having normally contacting ends and provided with means whereby the same may be attached to the interior of the skirt of the piston.
15. In combination with a piston having a slotted skirt and piston pin bosses, of a spring expander forming a closed figure generally oblong in shape and expansible lengthwise at right angles to the axis of said bosses and crosswise in the direction of the axis of the bosses and contacting at spaced points with the skirt intermediate the bosses and with the bosses, the expander having expansible curved formations to afford the desired expansibility.
16. A spring metal expander for a piston skirt having bosses, the expander being generally oblong in shape and having two flat parallel sides adapted to contact with the piston pin bosses, curved expansible formations at one end adapted to engage with the interior of one side of the skirt intermediate the bosses and formations adapted to engage the interior of the other side of the skirt intermediate the bosses.
- In testimony whereof, I have subscribed my name.
- RALPH R. TEETOR.
